DEVICE FOR TERRACING GRAVES

Earl C. McIntosh, St. Louis, Mo.

Application November 6, 1935, Serial No. 48,499

2 Claims. (Cl. 189—21.1)

This invention relates generally to a device for terracing graves, and particularly to a knocked-down frame or curbing which may be assembled together in order to simulate a stone curb.

5 The object of the invention, generally stated, is to provide a device constructed and arranged to be assembled together so as to form a terrace of the size corresponding with any particular 10 grave.

10 A further object of the invention is to provide a grave terracing device of the character mentioned wherein the respective sections are formed so as to simulate cut stone.

15 A more specific object of the invention is to provide a grave terracing device of the character referred to wherein various stone-like sections of short uniform length may be connected together to form a terrace of the desired size simulating stone.

20 Other objects will become apparent to those skilled in the art when the following description is read in connection with the accompanying drawings, in which:

25 Figure 1 is a perspective view of the grave terrace in connection with which a device of the present invention is employed.

Figure 2 is a perspective view of one of the side or end sections of the device shown in Figure 1.

30 Figure 3 is a similar view of a corner post.

Figure 4 is a fragmentary view illustrating the corner construction of the terracing device.

Figure 5 is a detail view illustrating one form 35 of device for connecting the respective sections together.

Figure 6 is a sectional view taken along line 6—6 of Figure 5.

Figure 7 is a view in side elevation showing 40 another embodiment of the present invention.

Figure 8 is a sectional view taken along line 8—8 of Figure 7.

Figure 9 is a perspective view corresponding to Figure 1 but showing another embodiment of 45 the device.

Figure 10 is a perspective view showing the longitudinal member employed in the embodiment of Figure 9.

Figure 11 is a perspective view showing the 50 end and corner member of the embodiment of Figure 9.

Figure 12 is a detail view showing the manner of connecting the side and end members of the embodiment shown in Figure 9.

55 In accordance with the present invention, gen-

erally stated, a series of metal sections which may conveniently be formed of sheet metal and of L-section may be formed in relatively short lengths and enameled so as to simulate pieces of cut stone. These enameled sections, being of 5 short length, may be assembled together in the desired number to form a terracing device of any required size. By thus forming the terracing device or curbing of relatively short sections of uniform length, it is apparent that great flexibility in size is obtainable, while at the same time the beauty of the device is accentuated.

Such enameled section may be of any desired color, such as to simulate marble, red granite, white stone, etc., and may be connected together 15 on the interior thereof where the connecting device will not be visible so as to give the effect of adjacent or abutting sections of stone. Moreover, the respective sections may be treated as by enameling with a slightly different color for 20 a short distance near the ends thereof or may be interposed with a separate narrow piece of slightly contrasting color so as to simulate mortar between the adjacent sections. It will be understood, of course, that the sections may be 25 made in plain colors so that the stone-like sections are in abutting endwise relation. Suitable means may be provided for anchoring the terracing device formed of the sections referred to to the earth and this may be accomplished 30 by interposing an end post, which, in accordance with one embodiment, is made of the same length as the side or end sections, and hence may be conveniently assembled and transported with said sections.

35 Referring now particularly to the drawings, the terracing device may comprise a series of side or end sections 1 which, as shown in Figure 2, are formed of L or angular section and may be made of sheet metal. These sections 1 may be coated, particularly on the exterior thereof, so as to produce enameled horizontal and vertical surfaces. A plurality of sections 1 may be assembled together with corner posts 2, as shown 40 particularly in Figure 3, it being understood that the desired number of sections 1 is employed to form a frame of the required size. On the interior of the frame the earth may be piled, so as to terrace the grave as shown at 3.

45 As shown particularly in Figures 3 and 4, the corner post 2 is of the same maximum dimensions as the side or end sections 1, while the portion 4 thereof, which is connected to and aligned with the adjacent sections 1 is of the same width 50 55

as the sections 1 so that these parts may be conveniently nested together for transportation and handling.

Suitable means may be provided for connecting the respective sections together. One embodiment of such means is illustrated particularly in Figures 5 and 6. As shown in Figure 2, the respective ends of section 1 may be provided with back turned flanges 5 in the formation of 10 which it will be understood that the exposed ends of the sections 1 will become slightly rounded so as to present an appearance simulating stone. If desired, however, the ends may be left sharp or angular, but in the embodiment illustrated it 15 is convenient to round the ends as the flanges 5 are formed. As shown in the drawings, a similar flange 6 is formed upon the horizontal surface of section 1, it being understood that the flanges are formed on the interior of the section 20 so as to be concealed from view when the device is in use.

As shown particularly in Figures 5 and 6, a slide 7 may be provided and may be slipped over flanges 5 of adjacent sections 1 so as to hold the 25 same together. A similar slide 8 is provided for corresponding flanges 6. In order to securely anchor the slide 7 in position, a slot 9 may be formed in the flanges 5 of the respective sections and arranged to cooperate with a tongue 10, 30 formed upon slide 7. It will be understood that the tongue 10 is upset so that the slide may be moved freely over the flanges but when in position with slot 5 may be driven down into the slot as shown in Figure 6, so as to securely hold the 35 slide in position.

Another embodiment of the connecting device is illustrated in Figures 7 and 8 where flanges similar to flanges 5 may be formed upon the respective sections 1. In accordance with this embodiment, the connecting device which may be 40 in the form of a slide 12 may have a portion 13 arranged to extend between the adjacent ends of sections 1 and there be exposed on the exterior. By enameling this exposed surface 13 so as to 45 slightly contrast with the color of sections 1 a mortar joint may be simulated and hence the appearance of the arrangement somewhat accentuated.

Referring now particularly to Figures 9 to 12 50 inclusive, another embodiment is shown in which the number of parts comprising the device is substantially reduced. In the case of this embodiment the device is composed of only four parts: namely, a pair of longitudinally extending or side members 20 and a pair of short side or end members 21. As shown in Figures 9 and 11 the end members include also corner members 27. As was the case with the previous embodiment, however, the corner members 27 extend 55 out for a substantial distance beyond the actual vertex thereof, so as to provide ample space for conveniently connecting the same to the adjacent members as by means of nuts and bolts 22 60 65 which extend through and connect cooperating

flanges 23 and 24 located respectively on the corner members and the side members as shown.

The side and end members as shown in Figures 9, 10, 11 are, as was the case with the previous embodiment, formed of sheet metal, such as 5 sheet steel, which is suitably enameled to simulate cut stone. The parts, as shown in Figures 9, 10 and 11 are, however, additionally provided with a pair of reenforcing flanges 25 and 26 extending longitudinally thereof, and at right angles to the respective main flanges of the angle section. These flanges 25 and 26 constitute reenforcing means whereby bulging of the relatively long members, shown in this embodiment, is substantially prevented and additionally provide 15 anchors for preventing displacement of the device both vertically and horizontally when filled with earth.

From the foregoing description it is apparent 20 that the present invention accomplishes its objects and that a grave terracing device is provided which is convenient to assemble and flexible so that it may be made of any desired size, while the respective sections are so formed as to 25 simulate stone, and being of the same dimensions may be conveniently handled. It will be understood, of course, that various modifications in the details hereinbefore set forth may be made without departing from the spirit of this invention. It is to be distinctly understood, therefore, 30 that the foregoing disclosure is to be interpreted as illustrative only and not in a limiting sense. Such modifications and the use of such individual features and sub-combinations of features, as do 35 not depart from the spirit of this invention, are, although not specifically described herein, contemplated by and within the scope of the appended claims.

Having described the invention, what is 40 claimed is:

1. A device of the kind described comprising, sheet metal side members of doubly flanged angle section enameled to simulate stone, separate sheet metal end members of doubly flanged angle section enameled to simulate stone, one of 45 the flanges on said members extending longitudinally along the lower edge thereof to stiffen the same and form a supporting foot and anchor to be covered by earth, and means within the angle for securing said end and side members 50 together.

2. A device of the kind described comprising, sheet metal side members of angle section provided with a reenforcing flange extending lengthwise thereof, separate sheet metal end members 55 of angle section provided with a reenforcing flange extending lengthwise thereof, said reenforcing flange on said members extending longitudinally along the lower edge thereof to stiffen the same and form a supporting foot and anchor 60 to be covered by earth, said end members being bent to form corners, means within the angle for securing said end and side members together.
